UNITED STATES PATENT OFFICE

2,366,150

SPRAYING APPARATUS

Clarence B. Yount, Dayton, Ohio, assignor to The Sherwin-Williams Company, Cleveland, Ohio, a corporation of Ohio

Application March 30, 1942, Serial No. 436,800

5 Claims. (Cl. 91—45)

This invention relates to a device for applying liquid spray materials and more particularly to a device for applying hot liquid spray materials.

It is a well known property of most liquids, semi-liquids and plastic materials that such liquids or materials may be applied more easily while hot than while cold. From this it can readily be seen that whenever coating materials are used that flow more freely while hot than cold, less solvent will be required for applying a coating while hot at a predetermined viscosity than would be required if the same coating material were applied while cold.

An object of this invention is to provide a device for applying coating materials while hot.

Another object of this invention is to provide a spray gun wherein the coating material at the spray gun is maintained within a predetermined temperature range so as to have available for use in spraying a liquid or semi-liquid at a predetermined temperature.

Another object of this invention is to provide a manual control for opening a by-pass permitting some of the coating material to be returned to the source of supply when the spray gun is not in use, to thereby maintain a substantially uniform temperature of the spray material at the spray gun.

Another object of this invention is to provide a thermostatically controlled by-pass circuit or passage that by-passes the fluid when the temperature drops below a predetermined temperature range, so as to maintain circulation of hot fluid.

Another object of this invention is to provide a release circuit responsive to manipulation of the spray gun for releasing the flow of the coating material during certain periods of time.

Another object of this invention is to provide a dual control for by-passing the hot fluid supplied to the spray gun, which dual control is responsive to movements of the trigger of the spray gun and to temperature variations.

Another object of this invention is to provide a by-pass circuit for a spray gun wherein the hot fluid supplied to the spray gun is permitted to be by-passed under predetermined conditions in response to the manipulation of the spray gun.

Another object of this invention is to provide a spraying device for spraying hot materials, which spraying device maintains a predetermined temperature at the spray gun, is cheap, economical to produce and at the same time dependable and efficient.

Other objects and advantages reside in the con-

struction of parts, the combination thereof and the mode of operation, as will become more apparent from the following description.

In the drawings,

5 Figure 1 is a schematic elevational view of a system for applying hot coating materials and other hot materials by means of a spray gun, with parts shown in section.

10 Figure 2 is a cross sectional view of the thermostatic valve, taken substantially on the line 2—2 of Figure 3 with parts shown in elevation.

Figure 3 is a side elevational view of a spray gun with manually controlled by-pass valve shown in section.

15 Numerous attempts have been made to spray coating materials, sometimes referred to as plastic coating materials, while hot, so as to economize upon the use of solvents. However, in the past, difficulties have been encountered in so

20 spraying hot coating materials, in that it is very difficult to maintain a uniform viscosity of the coating material entering the spray gun. The temperature may remain substantially constant when the spray gun discharges a predetermined amount of coating material continuously; but as soon as the spraying operation ceases, the coating material between the source where the heat is applied and the spray gun may cool and thicken to such an extent that it is practically impossible 25 to reestablish the flow of coating material through the spray gun.

In the embodiment disclosed herein a dual control for by-passing the hot fluid under predetermined conditions has been provided. This

35 dual control may include a thermostatically controlled valve for by-passing the fluid when the temperature drops below a predetermined value, at which time the fluid is by-passed, so as to supply hot fluid to the spray gun to maintain the proper fluid temperature. The other control may

40 be responsive to operations of the valve of the spray gun to permit the by-passage of fluid only when the spray gun valve is inoperative. These two controls may be used simultaneously, so that

45 the thermostatic valve can only by-pass fluid when the spray gun valve is closed. Furthermore, the thermostatic valve prevents the by-passage of fluid by the valve mechanism responding to the closing of the main valve in the spray

50 gun until the temperature of the fluid in the vicinity of the spray gun drops below a predetermined value. Instead of using both of these control means, only one may be used. For example, the thermostatic valve may be used to release the fluid when the temperature drops below a

predetermined value, without the use of the second control mechanism responsive to movements of the trigger. When the thermostatic valve is used without the second control mechanism, the fluid may continue to by-pass for some time after starting the operation of the spray gun. It may take some time for sufficient fluid to pass the thermostatic valve to close it.

On the other hand, if only the by-pass responsive to the operation of the spray gun is used, without the use of the thermostatic valve, fluid will be by-passed irrespective of the temperature whenever the spray gun valve is closed. This means that in the event the operator interrupts the operation of the spray gun temporarily to change articles, change position of the articles to be sprayed, or for any other reason closes the spray gun temporarily, fluid will begin to be by-passed immediately upon the closing of the spray gun valve. This means that fluid will continue to by-pass whenever the spray gun valve is closed, irrespective of whether or not the temperature of the fluid justifies some of the fluid being by-passed, so as to maintain the proper temperature at the spray gun.

Referring to the drawings, this system for supplying hot fluid, such as coating materials and other sprayable liquids or semi-liquids, to spray guns, includes a reservoir 10, having a supply of dissolved coating material. This coating material is pumped from the reservoir 10 by means of an electric pump 12 having an outlet 14 connected to a release valve 16, which maintains a constant pressure on the fluid in the outlet pipe or conduit 14. The fluid flows through the conduit 14, through one or more heating coils 18 mounted in suitable tanks 20. The opposite terminals of the heating coils 18 are connected by flexible hose 22 to a spray gun mechanism 24. This spray gun mechanism 24 will be described more fully later.

Hot water, or any other suitable heat transfer medium, is supplied to the tanks 20 from a suitable boiler 30, where the water or other heat transfer medium is heated and maintained at a predetermined temperature in any suitable manner. The heat transfer medium flows through conduits 32 into the tanks 20. Suitable valves 34 are mounted in the conduits so as to shut off the heat transfer medium from any selected tank 20. In the event a plurality of tanks are connected in the system and only one or more of the tanks are needed, the fluid medium is shut off from the remaining tanks. Return conduits 36 provide a return passage from the tanks 20 to the heater or boiler 30. Suitable valves 38 are used to close the return conduits whenever the tanks are not in use.

The fluid to be sprayed is forced by the pump 12 through the heating coils 18, where the fluid to be sprayed is heated to the desired temperature. For example, if the temperature of the spray fluid should be within a temperature range of from 150° to 170° F., the heat transfer medium in the tanks 20 is preferably maintained at a temperature of approximately 170°. As the spray fluid flows through the coils 18, it is heated to the desired temperature. The coils 18 are selected to have sufficient capacity to transfer the necessary heat from the fluid transfer medium to the spray fluid to maintain the desired temperature of the spray fluid during the maximum flow of spray fluid from the spray gun. In the event the system is used without operating all of the spray guns, valves 40 and 42, connecting

the spray guns that are not in use, are preferably closed.

The number of spray guns in the system is a matter of choice. Instead of operating one spray gun from each heating coil 18, the heating coils 5 may be selected so as to have sufficient capacity to take care of two or more spray guns. This is a matter of choice, depending entirely upon the system used and the particular requirements 10 thereof.

In spraying articles it is not feasible at all times to operate the spray guns without interruption. It may be found necessary to delay the spraying 15 operation while changing articles. It may be necessary to delay the spraying operation for the convenience of the operator and for numerous other reasons. In spite of the fact that the heating coils 18 maintain the proper temperature of the spray fluid in the coils, it does not follow 20 that the spray fluid in the hose 22 and the fluid actually in the spray gun is maintained at the proper temperature. As this fluid cools, it may become too thick for operation through the spray gun. That being the case, it is necessary to provide 25 means for maintaining the temperature of the spray fluid throughout the length of the hose and in the spray gun.

This has been accomplished by providing a by-pass spray fluid circuit or a return passage from 30 the spray gun to the reservoir 10. The by-pass circuit is closely associated with the spray gun 24. That being the case, a brief description of the spray gun will now be made.

The spray gun 24 includes a main body portion 35 50 having a handle-like portion 52 that forms a passage for the air intake. The air supply and the hose for supplying air to the spray gun has not been shown, as this is well known to those skilled in the art. Suffice to say, that the hose 40 is connected to the intake terminal 54. The forward end of the main body portion 50 of the spray gun includes a nozzle 60. The amount of fluid supplied to the nozzle is controlled by a valve 45 terminating in a valve stem 62 adjusted by a trigger 64 pivoted at 66 to the main body portion 50. The trigger 64 is provided with a slot 64a in which is positioned a pin 62a rigidly secured to the valve stem 62, so that the trigger 64 and the valve stem 62 travel together. As the trigger 64 is pulled, 50 it opens the valve 62 to the nozzle 60 and it opens the air valve 68 positioned in the upper portion of the handle-like portion 52. The valve stem 62 projects into a cylindrical cavity 52a in the upper end of the handle-like portion 50. The 55 valve stem 62 has fixedly secured thereto a collar 62b mounted within the cavity 52a. A helical coil spring 62c is mounted in compression between the collar 62b in the end wall of the cavity 52c. Whenever the operator releases the trigger 60 64, the spring 62c actuates the valve stem 62 to the left, as viewed in Figure 3, and rotates the trigger 64 in a clockwise direction, as viewed in this figure. A suitable adjustment for the trigger pull includes a knurled screw head 70. The 65 portion of the spray gun device that has been disclosed thus far is conventional and any suitable spray gun mechanism may be used.

A tubular projection or extension 80 connects the chamber of the spray gun with a suitable 70 fluid compartment, 82, that is preferably cylindrical and housing a suitable thermostatic valve 84. This thermostatic valve 84 is of the bellows or Sylphon type and is preferably filled with a suitable fluid, as is well known to those skilled 75 in the art. The spray gun fluid is supplied from

the hose 22 through a conduit 86 through the reservoir compartment 82, through the extension 80 to the spray gun valve. As it passes around the thermostatic valve 84, this valve expands or contracts in response to increase or decrease of the temperature of the fluid. If the temperature increases, it expands, so as to cause the needle valve 90 to be seated in and seal a passage 92 connected to a return passage 94, having its lower end connected to a hose 96 connected to a return pipe 98, permitting the spray fluid to be returned to the reservoir 10 whenever it is bypassed. In order to permit expansion of the Sylphon or bellows after the seating of the needle valve, the Sylphon is adjustably mounted on a resilient support.

The lower end of the bellows or Sylphon member 84 is attached to a screw threaded stud 100 merging into a shank 102 provided with a knurled head 104. The screw threaded stud 100 20 threadedly engages a bridging member 106, resiliently mounted upon a pair of springs 108 surrounding suitable bolts or guide members 110. This provides a yieldable support for the bellows or Sylphon 84, so that in the event this bellows or Sylphon expands after the needle valve 90 engages its seat, the lower end of the Sylphon, as viewed in Figure 2, will cause the bridging member 106 to move downwardly by compressing the springs 108. By adjusting the knurled head 104, the needle valve 90 may be adjusted to open the by-pass passage at any predetermined temperature, as for example, a temperature of 160°.

Whenever the temperature of the spray fluid drops below this predetermined temperature, the needle valve will open so as to cause the fluid to return to the reservoir 10, thereby supplying hot spray fluid from the heating coils 18 to raise the temperature of the spray fluid in the spray gun. By this arrangement, it can be readily seen that the temperature of the spray fluid in the spray gun may be kept at a temperature such that it has the proper viscosity for spraying.

In the event the needle valve 90 is in open position and the spray gun is at that time put into operation, it is very desirable that the return passage be closed instantaneously, so as to supply the entire pressure of the fluid to the spray gun without the use of the by-pass or bleeder passage. It will take a short period of time to heat the Sylphon sufficiently to close the needle valve after the valve in the spray gun is open. In order to close the by-pass passage or the bleeder circuit, a manually controlled valve is preferably inserted into the bleeder circuit, which closes the bleeder circuit immediately upon the opening of the spray gun valve. In other words, the valve in the bleeder circuit may be responsive to movements of the trigger 64.

As may best be seen in Figure 3, a valve 120, provided with a frusto-conical valve head, is spring urged to the right by a compression spring 122, urging the stem 124 of the valve member 120 against the trigger 64. The compression spring 122 is weaker than the compression spring 62c, so that as the operator releases the trigger 64, the compression spring 62c actuates the trigger 64 in a clockwise direction, as viewed in Figure 3. The trigger 64, when closing the valve 62, opens the valve 120. Immediately upon the trigger 64 being manually operated in a counter-clockwise direction, as viewed in Figure 3, to open the main valve 62 in the spray gun, the valve 120 is actuated into closed position, so as

to close the by-pass passage or bleeder circuit. By this arrangement, it can readily be seen that in spite of the fact that the needle valve 90 is held in open position, the by-pass passage or bleeder circuit is closed whenever the main valve is open, so as to supply the entire pressure of the spray fluid to the nozzle of the spray gun.

From the foregoing description it may readily be seen that a dual control for the by-pass passage or bleeder circuit has been provided, wherein one valve is manually controlled and the other is thermostatically controlled. The manually controlled valve responds to movements of the main valve, so that in this respect it is automatic.

15 Although the preferred modification of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

25 1. In a spraying device for spraying fluids while hot, the combination including means for supplying hot fluids, a spray gun having a main valve, tubular means for interconnecting the spray gun to said first mentioned means, and 30 dual control by-pass circuit means for returning fluid from the spray gun to the source of supply so as to maintain a predetermined temperature of the fluid supplied to the spray gun, said control means including a by-pass valve mechanism 35 having a valve, means for opening said last mentioned valve in response to the closing of the valve in the spray gun, and a thermostatically controlled valve for preventing the by-passing of fluid whenever the temperature of the fluid in the vicinity of the spray gun is sufficiently high to maintain the proper viscosity for spraying the fluid.

2. In a spraying device for spraying fluids while hot, the combination including means for supplying hot fluid, a spray gun having a main valve, tubular means for interconnecting the spray gun to said first mentioned means, and by-pass circuit means, said by-pass circuit means interconnecting the spray gun to said first mentioned 45 means, said by-pass circuit means including a by-pass passage, a thermostatically controlled valve opening the by-pass passage in response to a predetermined drop in the temperature of the fluid in the vicinity of the spray gun, and closing the by-pass passage in response to a predetermined 50 temperature of the fluid in the vicinity of the spray gun.

3. In a spraying device for spraying fluids while hot, the combination including means for supplying hot fluid, a spray gun having a main valve, tubular means for interconnecting the spray gun to said first mentioned means, and by-pass circuit means for providing a return passage from the spray gun to said first mentioned means, said 55 by-pass circuit means including a thermostatic valve and a by-pass valve, and means responsive to manipulation of the valve in the spray gun for closing said by-pass valve when the spray gun valve is open and for opening said by-pass valve when the spray gun valve is closed.

4. In a spraying device for spraying fluids while hot, the combination including means for supplying hot fluid, a spray gun having a main valve, tubular means for interconnecting the spray gun to said first mentioned means, and by-pass circuit

means for providing a return passage from the spray gun to said first mentioned means, said by-pass circuit means including a thermostatic valve responding to changes in the temperature of the fluid supplied to the spray gun, said thermostatic valve closing when the temperature is above a predetermined value and opening when the temperature drops below said predetermined value, and a manually controlled valve for opening and closing the by-pass circuit at the will of the operator.

5. In a spraying device for spraying fluids while hot, the combination including means for supplying hot fluid, a spray gun having a main valve, tubular means for interconnecting the spray gun to said first mentioned means, and by-pass circuit

means, said by-pass circuit means interconnecting the spray gun to said first mentioned means, said by-pass circuit means including a by-pass passage, a thermostatically controlled needle valve opening the by-pass passage in response to a predetermined drop in the temperature of the fluid in the vicinity of the spray gun, said thermostatically controlled valve including a fluid filled bellows supporting the needle of the valve, and a resilient support for the bellows opposite the needle valve permitting expansion of the bellows after closing of the needle valve, said thermostatically controlled valve closing the by-pass passage in response to a predetermined temperature rise of the fluid in the vicinity of the spray gun.

CLARENCE B. YOUNT.
